Attorney

UNITED STATES PATENT OFFICE.

DANIEL J. CROWLEY, JR., OF LAWRENCE, MASSACHUSETTS.

COMBINED MITER, BEVEL, SQUARE, AND ANGLE FINDER.

1,320,320.

Specification of Letters Patent.

Patented Oct. 28, 1919.

Application filed April 19, 1919. Serial No. 291,209.

To all whom it may concern:

Be it known that I, DANIEL J. CROWLEY, Jr., a citizen of the United States, residing at Lawrence, in the county of Essex and 5 State of Massachusetts, have invented certain new and useful Improvements in Combined Miter, Bevel, Square, and Angle Finders, of which the following is a specification.

10 This invention provides an adjustable square which may be readily adjusted for use as a miter, bevel or angle finder and which when not required for immediate use may be folded into compact form to be 15 stored in a comparatively small space.

The drawing illustrates a preferred embodiment of the invention, however, it is to be understood that in adapting the same to meet different conditions, various changes in 20 the form, proportion, and minor details of construction may be resorted to without departing from the nature of the invention as claimed hereinafter.

25 Referring to the drawing hereto attached, Figure 1 is a plan view of an adjustable square embodying the invention.

Fig. 2 is an edge view thereof.

Fig. 3 is a section on the line 3—3 of Fig. 1 looking to the right as indicated by 30 the arrow.

Fig. 4 is a transverse section on the line 4—4 of Fig. 1 looking in the direction of the arrows.

35 Corresponding and like parts are referred to in the following description and indicated in the several views of the drawing by like reference characters.

The square comprises a middle blade or arm 1 and side blades or arms 2 and 3, the 40 several blades being longitudinally slotted, as shown most clearly in Fig. 1. Each of the blades or arms is of similar or like formation and is provided with a longitudinal slot to provide for the various adjustments. A block 4 is located at one end of the 45 several blades or arms and the latter are pivotally connected thereto. A screw 5 or like fastening connects the blade 1 with the block 4 and passes through the longitudinal 50 slot of the blades or arms 2 and 3, thereby admitting of either one or both of the side blades or arms having both pivotal and slide- 55 able connection with the middle blade or arm 1. The block 4 constitutes a standard and saw guide and may be used in a variety of ways. The middle blade 1 is provided

with graduations 6 corresponding with the usual architectural scale of one-eighth of an inch to the foot, whereas each of the arms 2 and 3 is provided with a scale 7 graduated 60 in inches a fractional part thereof. The blades may be of any length or width and are preferably formed from sheet steel, the various scales being stamped therein.

A cross head 8 is slidably mounted upon 65 the middle arm 1 and is formed with a middle extension 9 and end extensions 10, the extensions 9 and 10 projecting in opposite directions. A portion of the cross head 8 and middle extension 9 enters the longitudinal slot of the arm 1, thereby preventing any pivotal movement of the cross head and causing the same to move on the arm 1 and at all stages of adjustment to maintain a position parallel to a given position. Pins 70 11 project from the extensions 10 and enter the longitudinal slots of the arms 2 and 3 and effect a pivotal movement of said arms when the cross head is moved on the arm 1. A screw 12 extends through the slot of the 75 arm 1 and passes through an opening in the extension 9 of the cross heads 8, and receives a hand nut 13. The head of the screw 12 overlaps the lower face of the arm 1 and acts jointly with the extension 9 to grip 80 the arm 1 so as to hold the cross head 8 in the required adjusted position.

When the cross head 8 is moved to the inner end of the arm 1, the side arms 2 and 3 are spread and alined, thereby forming a 90 T square. Movement of the cross head 8 to a position intermediate the ends of the arm 1 causes the arms 2 and 3 to assume an angle relatively to each other, the angle depending upon the position of the cross head 8. Obviously the arms 2 and 3 may be disconnected from the pins 11 and brought to a position so as to aline with each other and with the arm 1, thereby admitting of the device being reduced to compact form 95 100 for storing and carrying. The several scales provide for adjustment of the device to meet various requirements which will be determined by practice and skill in the use of the instrument.

105 The foregoing description and the drawings have reference to what may be considered the preferred, or approved, form of my invention. It is to be understood that I may make such changes in construction and arrangement and combination of parts, materials, dimensions, et cetera, as may prove 110

expedient and fall within the scope of the appended claims.

Having thus fully described my invention, what I claim as new and desire to secure by Letters Patent is:—

1. An instrument of the character specified, comprising a middle arm, a fastening at one end thereof, longitudinally slotted side arms supported on the middle arm and having the said fastening engaging the longitudinal slots thereof to admit of the side arms having independent pivotal and slideable movement and means slideable on the middle arm and having sliding engagement with the side arms through the longitudinal slots thereof and adapted to hold the several arms in the required adjusted positions.
2. A device of the character specified, comprising a middle arm, longitudinally slotted side arms having pivotal and slideable connection with the middle arm, a cross head slideable on the middle arm and having its ends engaging the respective side arms to effect a pivotal movement thereof and means for securing the cross head to the

middle arm in the required adjusted position.

3. A device of the character specified, comprising a middle arm having a longitudinal slot, a fastening at one end of the middle arm, longitudinally slotted side arms supported on the middle arm and having their longitudinal slots receiving the said fastening, a cross head slidably mounted on the middle arm and having oppositely extending middle and end extensions, the middle extension having a portion engaging the longitudinal slot of the middle arm and the end extensions having projecting elements engaging the longitudinal slots of the side arms and means for securing the cross head to the middle arm in the required adjusted position.

In testimony whereof I affix my signature in presence of two witnesses.

DANIEL J. CROWLEY, JR.
